APPARATUS FOR THE ELECTROLYSIS OF SOLUTIONS OF ALKALINE CHLORIDS.

1,378,829.

Specification of Letters Patent.

Patented May 17, 1921.

Application filed December 12, 1918. Serial No. 266,519.

To all whom it may concern:

Be it known that I, CLAUS NISSEN RIIBER, of Hans Hagerups gate 8, Trondhjem, in the Kingdom of Norway, have invented certain new and useful Improvements in Apparatus for the Electrolysis of Solutions of Alkaline Chlorids; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to the electrolysis of solutions of alkaline chlorids in apparatus with horizontal or substantially horizontal diaphragms through which the electrolyte passes from the anode compartment to the cathode compartment.

The existing apparatus of this type show the drawback that they can not with economical advantage give a strong hydroxid solution. The current output will then strongly decrease, the chlorin gas will be contaminated with carbon dioxid and oxygen, which render the further utilization of the gas difficult, the anodes are attacked by nascent oxygen, which results from secondary reactions and the diaphragm is successively dissolved by the strong hydroxid solution.

The object of the present invention is to eliminate these drawbacks. The construction of an apparatus, which could be used for carrying this invention into effect is diagrammatically illustrated in the accompanying drawing in which—

Figure 1 represents a vertical section; and Fig. 2 a vertical section taken at right angle to the section shown in Fig. 1.

A shallow case (1) of metal for instance copper or iron, which in the illustrated example serves as cathode chamber and container for the resulting hydroxid solution is at the top provided with a grate of metal rods (2) of a rectangular section arranged near to one another. The diaphragm (3) is supported upon this grate. On this case is placed a frame (4) made of concrete, shale slates or other material, which resists the action of the substances present. This frame which constitutes the anode compartment is at the top provided with a cover (5) of the

same kind of material as the frame itself and carries at the lower part the horizontal anodes (6), which as usual consist of electrode carbon, artificial graphite or magnetite.

A characteristic feature of the apparatus consists in the construction of the diaphragm and the manner in which it is produced.

It is old to construct horizontal diaphragms by placing upon a metal wire netting an asbestos plate, through which the liquid has to pass. This arrangement, however, has the drawback that the asbestos plate does not at every point lie in exact contact with the netting. Further such plates will easily obtain cracks, through which the principal quantity of the salt solution may pass. Moreover such long fibrous asbestos which must be used in the manufacture of asbestos boards or paper shows a comparatively low resistance to hydrochlorites, and alkaline hydroxid so that the manufacture of strong hydroxid solutions is rendered impracticable. It has also been attempted to use asbestos cloth, which could be covered with a layer of a pulverulent body such as sulfate of barium. This arrangement exhibits the fundamental disadvantage that the salt solution has not the same velocity at all parts of the diaphragm. It is obvious, that in the interstices between the individual threads of the asbestos cloth the velocity will be greater than right through a thread because in the latter instance the passage meets a much greater resistance. Such a difference in velocity however involves a decrease in current output. The movement of the salt solution toward the cathode as will be understood has for its object to force the wandering hydroxyl-ions back and this result can be attained only for that portion, which passes between the threads, while the movement of the liquid right through the threads is too slow to counteract the movement of the ions to any considerable extent. Also in this instance that sort of asbestos, which must be used in asbestos cloth has a lower resistance against the action of strong hydroxid solutions. Furthermore the present types of horizontal apparatus show the disadvantage that the meshes of the cathode netting are too large. It is obvious, that when these meshes are comparatively large,

salt solution which nearly completely escapes electrolysis will pass through that part of the diaphragm, which is disposed in the center of a mesh.

5 The ideal condition for the current output would obviously consist in infinitesimally small meshes or pores. Owing to the fact, however, that the hydrogen evolved on the top side of the metal netting must find 70 its way downward through the meshes, these latter cannot be so small that the capillary force resists the passage of the hydrogen to such a degree that the hydrogen instead of passing downward forces its way 75 right through the diaphragm body up into the anode compartment.

The apparatus constructed according to the present invention is provided with as fine meshes, (at least 25 and usually 400-1000 80 meshes on the square centimeter) as it is possible to use when the capillary force is considered. Hereby it is made possible that the places on the underside of the diaphragm, through which the current does not

85 pass, are practically eliminated. The advantage is hereby obtained that the hydrogen when escaping blows the formed hydroxid solution down into the bottom of the cathode compartment, so that it is removed 90 from the lines of current at the same time as it is prevented from entering by diffusion through the diaphragm.

Since the meshes are small the formed alkaline hydroxid solution will for a moment 95 fill up the interstices of the meshes and at the next moment the hydrogen produced, which must force its way downward will breach through this film of liquid and blow the hydroxid solution as small drops down 100 into the container. A regular shower of hydroxid solution is hereby produced and removed from the cathode.

The principal advantage of the fine metal netting, however, consists therein that it 105 allows the production of a diaphragm without agglutinants from asbestos wool, asbestos flour, glass wool or other fibrous or pulverulent material with capacity of resistance directly upon the metal netting.

50 For this purpose a paste or semiliquid suspension of the asbestos wool or powdered asbestos is uniformly spread upon the wire netting and the water is removed by free dropping or by means of suction, that is substantially in the same manner as is usual in 110 the manufacture of paper or paste-board.

Such a coating will show the advantage of being everywhere in intimate contact with the surface of the wire which is of greatest 115 importance for the electrolysis. It is obvious that if parts of the cathode are not in direct contact with the diaphragm, the passage of the electrical current will be prevented and the wire as a consequence of the 120 evaporation taking place will be liable to

be covered by solid caustic soda, which has an unfavorable action upon the electrolysis.

It might be expected that a diaphragm which is produced in the manner described and which will consist of fibers or granules being comparatively loosely connected would prove not to be permanent during the electrolysis, when it is not strengthened by a firmly coherent layer for instance of asbestos pasteboard, asbestos cloth or a thin 75 coating of cement mortar. During the electrolysis gaseous hydrogen is constantly evolved on the top side of the wire netting or screen at the point where the particles of the diaphragm rest and it might be feared 80 that this gas would gradually loosen the particles, so that they could be washed down into the cathode compartment by the hydroxid solution while the gas would constantly work its way up through the loose 85 mass and finally enter into the anode compartment. Experiments have given the surprising result, however, that this fear is quite groundless.

The powdered asbestos necessary for this 90 purpose need not contain long flexible fibers but can consist of short rigid needles, which as experience has shown have a greater power of resistance against the action of 95 hypochlorite and caustic solution.

A diaphragm of this nature is also in other respects of special advantage. In a good diaphragm all pores and interstices should as far as possible be of equal size. If this is not the case the movement of the salt solution will substantially be limited to the large 100 pores, while the hydroxyl-ions wander as quickly through small as through large pores.

Pores which are as like in size as possible 105 can in the present instance be obtained by the use of washed asbestos flour, that is a powdered asbestos having particles of a size as equal as possible. The coarser powder is then placed at the bottom. Upon this is 110 placed the powder of middle size and at the top the finest washing fraction. This latter fraction is necessary because the diaphragm not only has the function to prevent the chlorine from attacking the produced caustic 115 solution but also to offer such a high friction to the passage of the anode liquid that the velocity of the passage of the liquid becomes the right one for the desired strength of the hydroxid solution.

120 As a matter of course the density of the diaphragm may be increased by placing above the layers of asbestos a coating of a fine powder which is able to resist the chemical actions in question such as calcined alumina, silica, iron oxid, sulfate of barium and the like.

On the top of the diaphragm itself may be suitably be placed a layer of a loose substance for instance glass wool or asbestos 130

wool of a long fibrous character to prevent currents in the upper part of the anode liquid from causing disturbance in the horizontal layer of liquid directly above the 5 diaphragm or to effect dislocations of the particles of the diaphragm.

A loose coating of this nature will also prevent precipitated anode slime from contaminating the diaphragm mass proper. It 10 will be understood that the material in the type of diaphragm above described has the advantage as compared with plates, cloth and the like that it can be used anew after a simple refining by washing, when after an 15 extended use it has been removed. Such previously employed mass is even better than freshly prepared mass because such small quantities of soluble substances as may be present are removed by the passage 20 of the electrolyte.

It is an important condition for obtaining a good current output that the current density is the same at every point of the cathode netting. As this latter according to 25 the present invention must have small meshes and consequently also fine threads it will have a low power of conduction. It is therefore necessary to take special measures to assure a uniform current density. The 30 netting itself should be made of a metal of very good conductivity for instance of copper but preferably of silver. More especially however, the desired abundant supply of current may be obtained by supporting 35 the netting upon a row of metal strips (2, 2 . . .) arranged near to one another. These strips should be made of copper or other suitable material.

This strong supporting structure of strips 40 also has the effect that the diaphragm lies quite horizontal and does not yield under the weight of the anode liquid, this being of importance for the efficient working of the diaphragm.

45 The described fine netting may be suspended directly on the said strips or an interposed perforated metal sheet or upon another wire netting, which then should have meshes of a larger size. By means of these arrangements a still more uniform density of current is attained.

The advantageous working of the horizontal arrangement of electrodes being due to the formation of layers care must be taken 55 that no currents are produced in the anode liquid, whereby the different horizontal layers of the liquid are mixed with one another.

It is of particular disadvantage in this respect that the diaphragm on account of its 60 electrical resistances produces heat which may cause the liquid at the bottom of the anode chamber to rise, while the loss of heat through the side walls and the cover of the anode compartment effects a cooling of the 65 higher positioned part of the liquid, so that

it will descend. These circumstances both promote an injurious flow of currents.

The currents may be counteracted by heating the salt solution before it is introduced into the electrolyzing chamber through the 70 pipes (8, 8, 8).

According to the present invention the formation of currents can be further counteracted by heating the walls of the anode compartment and by arranging a heatinsulating coating (9) upon the cover of the electrolyzing chamber and the side wall of the anode chamber while giving the air free access to the metal casing of the cathode compartment, whereby the diaphragm layer 75 80 is indirectly cooled. The heating of the walls of the electrolyzing chamber can be effected by means of electric current, the conductors (10, 10) passing current to the horizontal anodes being given such a small 85 sectional area that the desired heat of resistance is produced. Also other parts of the anode chamber may be heated by electrical resistance heat where this is found to be 90 desirable. The horizontally positioned anode rods (6, 6, 6) are in the illustrated example at the ends provided with inclined surfaces corresponding to inclined surfaces on the conductors (10, 10). The rods can then easily be put into their proper place by 95 being pressed downward, whereby they are wedged so tight that a good contact is attained. This arrangement also allows of easily removing the anode rods, when they must be shifted or the diaphragm is to be 1 inspected.

I claim:-

1. The method of making diaphragms for use in electrolyte chambers which consists in securing upon a metal netting a fibrous 1 material in a substantially pulverulent condition without an agglutinent, from a liquid containing the material in suspension.

2. For use in an electrolytic chamber, a diaphragm including a metal netting and 110 fibrous substantially pulverulent material deposited thereupon without an agglutinent from a bath containing the material in suspension.

3. Device according to claim 2 in which 115 the material is asbestos.

4. Device according to claim 2 in which the netting has at least 25 meshes per square centimeter.

5. Device according to claim 2 in which 120 the material is arranged in layers of different degrees of fineness from the netting upwardly.

6. Device according to claim 4 including under the netting one or more reticulated 125 metal structures of larger mesh than the netting.

7. An electrolytic chamber including a horizontal diaphragm composed of a wire netting and fibrous substantially pulverulent 130

- material deposited thereon without an ag-
glutinant from a bath containing the mate-
rial in suspension and dividing the cham-
ber into a cathode compartment and an an-
ode compartment.
8. An electrolytic chamber of the charac-
ter described, including a diaphragm sepa-
rating the chamber into a cathode compart-
ment and an anode compartment, electrodes
10 and means for insulating the anode compart-
ment against heat exchange with the outside.
9. An electrolytic chamber of the character
described, including a diaphragm separating
15 the chamber into a cathode compartment
and an anode compartment, electrodes and
electric conductor means leading from the
anodes, said conductor means including a
resistance element within the chamber for
liberating heat.
- 20 10. Apparatus according to claim 9 in
which the said resistance element extends
along a wall of the chamber and is connected
to all the anodes.
- 25 11. Apparatus according to claim 9 in
which the said resistance element is substan-

tially co-extensive in length and height with
a wall of the chamber.

12. An electrolytic chamber of the charac-
ter described, including a diaphragm sepa-
rating the chamber into a cathode compart-
ment and an anode compartment, electrodes,
means for insulating the anode compart-
ment against heat exchange with the outside
and an electrical resistance element in the
chamber connected with the anodes for lib-
erating heat.

13. In an electrolytic chamber the combi-
nation of horizontal electrode rods having
slanting downwardly converging end sur-
faces and conductor elements supported 40
upon opposite walls of the chamber having
inclined faces adapted to form seats for the
ends of the rods.

In testimony that I claim the foregoing
as my invention, I have signed my name in 45
presence of two subscribing witnesses.

CLAUSS NISSEN RIIBER.
